DISPLAY CONTAINER OR RECEPTACLE

Morris M. Einson, Yonkers, N. Y., assignor to
Einson-Freeman Co., Inc., Long Island City,
N. Y., a corporation of New York

Application February 1, 1932, Serial No. 590,143

3 Claims. (CL 206—44)

The present invention has relation to receptacles, trays or baskets useful for containing merchandise which is intended to be displayed on a store counter or elsewhere.

5 The improved device belongs to a class of receptacles, trays or the like which are in a collapsible form so that they may be conveniently packed within the packing container for the merchandise. In the use of such devices the 10 merchandise, for example candies put up in say five cent packages, are packed in a gross container but instead of using a costly container decorated with advertising matter, etc. such as 15 commonly used, the gross container may be composed of a rough and inexpensive material without decorations. The trays or the like such as referred to above, are decorated with suitable display or advertising matter and instead of displaying the entire contents of the gross package, 20 only a part of said contents may be taken out and placed in the tray en masse thereby giving an ideal display of the merchandise and facilitating the dispensing of the articles contained therein.

25 The improved container is designed so that it will collapse or fold into the smallest possible compass to get a tray of the maximum size within a given package. The improved device is furthermore designed so as to facilitate the manufacture thereof and also the assembling or 30 setting up of the same.

The device according to this invention is also designed so as to offer advantages as regards economy in production for with this invention 35 the article may be composed of material, preferably paper-board, which is prepared and printed on one surface only; furthermore due to the construction of the device the maximum rigidity is obtained; therefore board of comparatively 40 light weight may be employed with advantage.

According to the present invention the improved article is composed of two blanks; one blank forming the side and end walls and bottom of the device and the other blank provides 45 a display placard, the back wall of the device, and also serves to connect the two ends of the first blank together to form a receptacle.

The invention is shown and described herein-after in a form in which the receptacle is of 50 hexagonal shape but it will be understood that the tray may be of other polygonal shapes for example octagonal, square or rectangular and in carrying out the invention as applied to boxes of the shape illustrated or of other shape, the 55 improved box will embody the novel features

hereinafter described with reference to the accompanying drawing, wherein—

Figure 1 is a perspective view showing the improved article set up a position for operation;

Figure 2 is a sectional view taken on line 2—2 of Figure 1;

Figure 3 is a plan view of the blank of which the body of the improved device is mainly composed;

Figure 4 is plan view of another blank which 10 provides a display and connecting back for the improved device; and

Figure 5 is a top plan view showing the device in a collapsed position.

Referring to said drawing, the improved tray 15 or container, in the preferred form as shown, is composed of the body blank 1 which is in the form of a strip divided by crease lines *a* into tapering portions 2. Said strip 1 is cut out in the radius of a circle which is in accordance 20 with the angular inclination desired for the walls of the tray. The sections 1 preferably have straight top and bottom edges as shown so that said edges, in the set up position of the tray, will be in the same plane all around. It will, 25 however, be understood that the upper edge of said portions may be serrated or otherwise made fancy to add to the ornamentation of the device. An extension 3 depends from one of the portions 1 and this extension 3 provides the bottom of 30 the tray and is hingedly connected along the crease line *b* which lies slightly above the bottom line 4 of the strip 1. The object in so off-setting this hinge, is to bring the same above the bottom line of the device as shown in Figure 1 35 and thereby insure an even base for the tray when standing in the operative position.

A separate sheet blank 5 forms the back wall 40 of the container body 1 and this blank also provides a display placard 6 which rises prominently above the back top edge of the container when in the set up position. This sheet blank 5 also provides a connecting means for the two ends of the strip 1 which latter has the lap portions 7 adapted 45 to be adhesively or otherwise secured to the tapered end 8 of the sheet 5. In the securing means shown this end 8 is provided with a slot 9 having extended cut edges 10. The end of the bottom member 3 is creased at 11 to permit the 50 downward bending of the same and this end carries tongue 12 having barbs 13. This tongue engages the slot 9 and the extended cut edge 10 permits the insertion of the barbs 12 which in the 55 operative position engage said edges and thus

lock the securing means against accidental release.

The said bottom portion 3 is creased at 14 to allow upward folding thereof; thereby the device may be collapsed even when the bottom is in the secured position. It will be understood that the free end of the bottom forming portion 3 may be adhesively or otherwise permanently secured to the end 8 of the card or back forming and connecting sheet 5 but in practice it has been found that the operation of the tongue and slot securing means facilitates the manufacture of the improved device.

The formation of the improved device of a two piece blank constructed and arranged as shown particularly facilitates the economical manufacture of the device and it will be noted from the stipple shading of the set up device, shown in Figure 1, that in the assembling of the two blanks the prepared or printed surfaces of the blanks are reversed so as to bring said printed surfaces into view. If the container were composed of a single blank obviously the exposed surface at the back of the device would be the reverse or unprinted surface in such instances where the composing material of the box is prepared and printed on one side only. In this case the show card 6 would have to be folded on itself in the usual manner or a separate card would be employed to permit the reverse exposure.

The improved container, as stated, is packed within the gross container along with the merchandise to be displayed. When so packed the device is in its folded or collapsed position as shown in Figure 5. In this condition the connection of the free end of the bottom forming portion would preferably have been effected in the first folding of the container.

The operator in setting up the improved receptacle is only required to open the folded device by a simple and self-apparent operation. A portion of the merchandise may then be taken from the packing container and placed en masse within the receptacle portion of the display container. The weight of even a small portion of the merchandise will tend to keep down the bottom and when the bottom is so held pressure is created to spread the walls where they are held in a rigid set up position.

It will be understood, as previously stated, that the container may be of different polygonal shapes and it should be noted that the bottom forming portion of the container would then be of a conforming shape so as to closely fit, thereby presenting also friction which will tend in conjunction with pressure, to retain the bottom and walls in place.

Various modifications may be made in carrying out the details of the invention hereinbefore described and it is to be understood that any modification coming fairly within the terms of the appended claims shall be covered thereby.

I claim:

1. A container of the class described composed of a strip of sheet material having its ends united by an intermediate connecting piece and folding to form walls of the container, a bottom forming piece hingedly and detachably secured respectively at the front and rear ends to said strip and said bottom forming piece being foldable on itself to permit collapsing of the container without release of the detachable connection.

2. A container of the class described composed of a strip of sheet material having its ends united by an intermediate connecting piece and folding to form walls of the container, a bottom forming piece hingedly and detachably secured respectively at the front and rear ends to said strip, the front hinge being located above the bottom edge of said strip and said bottom forming piece being foldable on itself to permit collapsing of the container without release of the detachable connection.

3. A container of the class described composed of a strip of sheet material having its ends united by an intermediate connecting piece and folding to form walls of the container, a bottom forming piece hingedly and detachably secured respectively at the front and rear ends to said strip, said bottom forming piece being foldable on itself to permit collapsing of the container without release of the detachable connection, and said detachable connection comprising a tongue and slot device with interlocking means preventing accidental pulling out of said tongue.

MORRIS M. EINSON.
